UNITED STATES PATENT OFFICE

127,583

DESIGN FOR A LABORATORY UNIT

Joseph Ralph La Vietes, Brooklyn, N. Y.

Application March 5, 1941, Serial No. 99,359

Term of patent 7 years

To all whom it may concern:

Be it known that I, Joseph Ralph La Vietes, a citizen of the United States, residing in the Borough of Brooklyn, county of Kings, city and State of New York, have invented a new, original, and ornamental Design for a Laboratory Unit, of which the following is a specification, reference being had to the accompanying drawing, forming a part thereof, in which:

Fig. 1 is a front elevational view of the labora-

tory unit showing one of the doors in open position;

Fig. 2 is a top plan view thereof with the top lid on the left of the table top removed; and

Fig. 3 is a side elevational view thereof.

I claim:

The ornamental design for a laboratory unit, substantially as shown.

JOSEPH RALPH LA VIETES.
